UNITED STATES PATENT OFFICE.

HAROLD OSMOND BURROUGHS AND ERIC STANLEY BURROUGHS, OF LIVERPOOL,
ENGLAND.

LOOSE-LEAF BINDER.

Application filed January 15, 1923. Serial No. 612,805.

To all whom it may concern:

Be it known that we, HAROLD OSMOND BURROUGHS and ERIC STANLEY BURROUGHS, subjects of the King of Great Britain, and residents of Liverpool, England, have invented certain new and useful Improvements in Loose-Leaf Binders, of which the following is a specification.

This invention relates to loose leaf binders such as ledgers or the like of the type comprising a pair of clamping bars capable of being drawn together by thongs or tapes. In such apparatus a ratchet wheel and a pawl have been provided to prevent backward rotation of the winding spindle and means has also been provided on the actuating key for temporarily disengaging the pawl from the ratchet when required in order to permit slackening of the binding tapes.

According to this invention, the backs or covers of the loose leaf binder, such as a ledger, are pivotally connected to the clamping bars which latter are adapted to be drawn together by thongs or the like in the usual way. By so pivoting the backs or covers of the binder and the clamping bars, pivotal movement of the covers to open the book does not impart any movement to the clamping bars and, consequently, the opening or closing of the covers does not disturb the grip obtained on the loose leaves by the bars. The thongs or the like, which pass through apertures in the loose leaves and in the clamping bars in the usual way, are connected together by a yoke piece or the like to which is coupled a flexible cord winding on a pulley or disc fitted or provided with a ratchet which is normally engaged by a spring controlled pawl. The disc is provided with a cam surface or the like preferably of circular contour and having a face or abutment at one end of the cam. The key is provided with a projection which is adapted to be entered through a slot in the ratchet disc when it is desired to operate the mechanism, the projection, when the key is turned in one direction, engaging the face or abutment of the cam and turning the disc to wind and tighten up the tapes or thongs in order to bind the ledger, but if the key be rotated in the opposite direction, the projection by riding up the slope of the circular cam sets up longitudinal movement of the key which movement disengages the

spring controlled pawl from the ratchet and frees the binding tapes.

A loose leaf ledger in accordance with this invention is illustrated in the accompanying drawings in which Fig. 1 is an elevation showing the ledger covers opened out and the leaves removed. Fig. 2 is an edge view. Figs. 3, 4, and 5 are fragmentary elevation, side, and end views respectively to a larger scale showing the pivotal connection of the ledger back to the clamping bars. Fig. 6 is a rear elevation of the ratchet disc and casing. Fig. 7 is a diametral section through the casing with the operating key in position and Fig. 8 is a front elevation with the top of the casing cut away. Fig. 9 is a detail of the ratchet disc itself with part of the flexible cord attached.

In a suitable construction the clamping bars consist of channel or solid elements 1 having apertures 2 through which pass the binding tapes or thongs 3, the ends of the thongs connecting to one clamping bar 1^a, and the other ends of the thongs being connected by a yoke 4 to which is coupled a flexible cord 5 such as a light stranded wire rope. The other end of this stranded wire is connected at 6 to the periphery of a disc 7 on which is secured or formed a ratchet 8, the disc being rotatably mounted in a casing 9 which carries a spring controlled pawl 10 normally held in engagement with the ratchet. The pawl may, as shown, be formed on the end of a plate secured to the casing loosely by a screw 11 a light leaf spring 12 being secured at 13 to the casing and at its other end 12^a to the pawl.

The eye of the ratchet disc is provided with a longitudinal groove 14 to pass a projection 15 on the cylindrical shank 16 of the operating key, which groove terminates in a space between the ends of a circular cam 17. Consequently, when the key is inserted and its projection passes down the longitudinal groove the projection 15 ultimately becomes positioned in the space 18 between the ends of the cam, and by turning the key in one direction the projection engages the high end 17^a of the cam and positively rotates the whole ratchet disc to wind up the flexible element 5 and tighten the tapes 3. The clamping bars 1, 1^a are thus drawn tightly together and the leaves a consolidated.

Reverse turning of the key, however,

causes the projection 15 to ride along the sloping cam face 17^b, which action pushes the key inwardly, depressing the spring 12 and disengaging the pawl 10 from the ratchet 8, thus freeing the tapes by permitting the ratchet disc to rotate back and permitting the clamping bars 1, 1^a to be opened.

The clamping bars 1, 1^a are pivotally connected at each end of the backs or covers 19 of the binder. This may be effected by providing brackets 20 on the backs or covers having lugs 21 which engage slots in the ends of the clamping bars through which lugs and the clamping bar ends pivotal screws 22 are passed. Consequently, the clamping bars are pivotally connected to the backs or covers and, when the binding mechanism is tightened up, the clamping bars are free to accommodate themselves easily and firmly against the loose leaves and at the same time when the clamping bars have been tightly drawn together the opening of the covers or backs of the binder does not disturb the grip of the clamping bars, which is apt to occur in other forms of such loose leaf binding mechanisms where the clamping bars are rigidly carried by such covers. The clamping bars may be of channel section and may be made up of sheet metal, as may also be the case with the brackets 20 on the covers.

The thongs 3, yoke 4, flexible wire 5, stranded cord or the like, together with the ratchet disc 7 and its casing, may all be housed in one of the covers of the binder as shown.

In order to ensure that the clamping bars shall obtain a grip on the leaves even when the solid clamping position corresponds to a position of the pawl midway between two teeth on the ratchet disc, instead of the flexible element 5, being directly connected they may be connected to the yoke 4 through a stout spring so that a slight resiliency is obtainable in tightening up the clamping bars and thus permit of the loose leaves being securely held, even when the normal locking position of the pawl 10 is midway between two ratchet teeth, the fall back of the disc against the pawl not slackening the clamping bar grip owing to the spring connection.

The edges of the loose leaves are punched

with slots the paper at the rear edge of the leaves beyond each slot being divided so that the lugs of paper which enclose the slots at the rear may be bent out to open the slots and pass the leaves over the thongs in well known manner, the lugs being subsequently bent into the plane of the leaf behind the thongs.

We claim:

1. A loose leaf binding mechanism, comprising, binding elements connected to a common yoke, a ratchet disc by the rotation of which the binding elements are tightened, a flexible cord winding on the disc and connected to the yoke, a spring controlled pawl normally engaging the ratchet, a cam surface on the disc, an abutment on the disc, a key for operating the disc, said key having a projection which engages the abutment and rotates the disc when the key is turned one way, but engages the cam and causes the key to disengage the pawl when the key is turned the other way.

2. A loose leaf binding mechanism, comprising, binder covers, clamping bars pivotally connected to the covers, binding elements, a ratchet disc by the rotation of which the binding elements are tightened, a spring controlled pawl normally engaging the ratchet, a cam surface on the disc, an abutment on the disc, a key for operating the disc, said key having a projection for engaging either the abutment or the cam.

3. A loose leaf binding mechanism, comprising, binder covers, clamping bars pivotally connected to the covers, binding elements, a ratchet disc by the rotation of which the binding elements are tightened, a spring controlled pawl normally engaging the ratchet, a circular cam surface on the disc, a hole in the ratchet disc, a groove in the hole, an abutment on the disc, a key for operating the disc, said key having a projection which is entered through the groove for engaging either the abutment or the cam.

In testimony whereof we affix our signatures in presence of two witnesses.

HAROLD OSMOND BURROUGHS.

ERIC STANLEY BURROUGHS.
